UNITED STATES PATENT OFFICE.

HENRY A. CHASE, OF BOSTON, MASSACHUSETTS.

AUTOMATIC TIME-STAMP.

SPECIFICATION forming part of Letters Patent No. 445,161, dated January 27, 1891.

Application filed July 31, 1890. Serial No. 360,557. (No model.)

To all whom it may concern:

Be it known that I, HENRY A. CHASE, of Boston, county of Suffolk, State of Massachusetts, have invented an Improvement in Automatic Time-Stamp, of which the following description, in connection with the accompanying drawings, is a specification, like letters and figures on the drawings representing like parts.

10 This invention has for its object to improve that class of automatic time-stamp which stamps the time on a strip of paper.

In accordance with this invention the stamp has been so constructed and mounted in the frame that it acts to print the time on the top of a strip of paper, where it remains in full view, thus obviating overturning the strip of paper to see the time. I have also combined with the time-stamp a time-indicating dial 20 and pointer, which is exposed to view at the top of the machine, so that a person looking at the stamp may see the time, using it as a clock.

The printing devices herein represented 25 comprise a fixed plate having thereon rubber or other characters representing the hours of the day, a pointer adapted to be turned to point to the hour, and another pointer adapted to be turned to indicate the minutes of the 30 hour, it being understood that the hour-pointer makes a complete revolution each twelve hours and the minute-pointer a complete revolution each hour, suitable mechanism being provided for that purpose. As herein shown, 35 the said hour and minute hand pointer-arbors are actuated by or through an electro-magnet and intermediate devices, which give to said arbors an intermittent or step-by-step movement, the said magnet being included in an

40 electric circuit containing a circuit-changing device moved or controlled by a clock or other motor. The platen over which the paper is moved and by which the paper is lifted against the stamp is shown as adapted to be attracted 45 by an electro-magnet, and I have also shown it as adapted to be moved by hand, if desired.

The time-stamp has combined with it devices to indicate A. M. and P. M., and dating devices to indicate the day of the month, the 50 month, and year are provided, which may be turned as required by hand.

Figure 1 shows in vertical section a time-

stamp embodying this invention; Fig. 2, a horizontal section of the time-stamp shown in Fig. 1, taken on the dotted line x x ; Fig. 55 3, a plan view of the time-stamp shown in Fig. 1, the cover or top plate being removed; and Figs. 4 and 5, details to be referred to.

The main frame-work consists of a hollow base portion A and a hollow top portion B, 60 provided with a cover C of glass. The base portion A contains an electro-magnet a, which is supposed to be included in any usual electric circuit. The armature a' of this electro-magnet a is attached to a rod or bar a², movable horizontally in a bearing a³ and connected at one end to a bell-crank lever a⁴, pivoted at a⁵, said lever being in turn connected to a supporting rod or bar a⁶, attached to a platen a⁷, which, as herein shown, rests normally on 65 the top of the frame A, and the armature of the electro-magnet is normally retracted. When the armature a' is attracted, the rod a² will be moved in the direction of the arrow, Fig. 1, and lift the platen. A spiral spring 70 a¹¹, encircling the rod or bar a² and bearing at one end against the bearing a³ and at its other end against a hub a⁸ secured to the said rod or bar, serves to restore the platen into 75 its normal position, and also to retract the armature. The armature a' has a short arm a⁹, slotted horizontally, as at a¹⁰, to receive a pin a¹² of a bell-crank lever a¹³, pivoted at a¹⁴, said lever being loosely connected to a rod or bar a¹⁵, extended vertically through the top 80 portion B of the frame, and provided with a knob a¹⁶, by which said rod a¹⁵ may be depressed to lift the platen. A spiral spring a¹⁷ on the bar a¹⁵ keeps the knob a¹⁶ in its elevated position. When the armature a' is attracted, 85 the slot a¹⁰ will follow on the pin a¹².

Two rollers b b', journaled in the frame B above the platen a⁷, one at each side, support or carry a suitable inking-ribbon b². These rollers b b' have thumb-nuts b³ b⁴ (see Fig. 3) 90 by which to turn them.

The printing device herein represented consists of a stationary circular plate c, having on its under side characters representing the hours of the day. Co-operating with this 100 plate is the hour-indicating pointer c', secured to a rotatable arbor c², having its bearings in the frame B, and the minute-indicating pointer c³, secured to a sleeve c⁴ on the arbor

c^2 . The sleeve c^4 has fixed to it a toothed wheel c^9 , which engages a pinion c^8 , (see dotted lines, Fig. 3,) fixed to an arbor c^7 , carrying a toothed wheel c^6 , which engages a pinion c^5 , (see dotted lines, Fig. 3,) fixed to the arbor c^2 . The toothed wheel c^9 has a complete revolution each hour and with it the pointer c^8 , and through the train of gears above described the pointer c' is turned a complete revolution once in twelve hours. As herein shown, the toothed wheel c^9 derives its rotation from a toothed wheel d , secured to the arbor c^2 , said wheel having, it will be supposed, sixty teeth, and being moved intermittently, or by a step-by-step device. This step-by-step device consists of a rod or bar d^2 , attached to the armature d^3 of an electro-magnet d^4 , and having rigidly secured to it a push-pawl d^5 , while another push-pawl d^6 is secured loosely to the outer end of said rod or bar d^2 , said loose pawl having an arm or projection d^7 , which, when the armature d^8 is attracted, strikes a fixed pin d^9 and turns the said pawl d^6 on its pivot in the direction of the arrow thereon, and thereby moves the said toothed wheel d . This step-by-step device referred to is substantially the same as ordinarily used in electric clocks. As herein shown, the magnet d^4 is supposed to be included in an open circuit, so that each time the said magnet is energized the armature d^8 will be attracted and the toothed wheel d moved by means of the pawl d^6 the distance of substantially one-half a tooth, and when the said armature is retracted the pawl d^6 will engage and move a further distance equal to substantially one-half a tooth, so that by a complete vibration of the armature the wheel will be moved forward one tooth.

d^{10} (see Fig. 3) represents the retractile spring for the armature d^3 .

The frame B has a fixed stud or post e , provided at its lower end with the letter M, and opposite said post is a stud e' , having a disk e^2 , provided with the letters A P, so that when this lifting-disk is in one position the letter P will be exposed to print, and when in its other position the letter A will be in proper position to print. This disk e^2 is arranged to be turned automatically once in twelve hours, and I have shown one train of gearing for accomplishing this result, said gearing consisting of a toothed wheel i , secured to the shaft or arbor c^7 and engaging a toothed wheel i' , secured to a shaft or arbor i^2 , which carries a pinion i^3 , which engages a toothed wheel i^4 , secured to a shaft or arbor i^5 , carrying a cam-disk i^6 . The lever i^8 , pivoted at i^7 , has at one end a friction-roll i^9 which co-operates with the cam-disk i^6 , (see Fig. 5,) and at its other end said lever has a pin or stud i^9 , which strikes one or another projection i^{10} , secured to the stud e' , and at substantially right angles to said projections i^{10} two projections i^{12} are arranged, having flat faces which co-operate with a flat spring i^{13} .

As the lever i^8 is moved on its pivot by the cam i^6 the stud e' will be turned so that one of the projections i^{12} will bear against and move the spring i^{13} until the said projection passes its dead-center, after which the spring will act on the opposite side of the said projection i^{12} and thereby give the stud a quick turn. By this mechanism the stud e' will be turned substantially one-fourth of a revolution slowly by means of the cam i^6 , and then another fourth of a revolution by means of the spring i^{13} .

On the plate u an auxiliary dial u' is arranged, indicating the hours, and an hour-hand u^2 is secured to the arbor c^2 , which moves over the said dial to thereby indicate to the eye the exact time which is to be printed by the printing devices concealed from sight. A thumb-nut u^3 is also secured to the arbor c^2 , by which it may be turned. A suitable piece of glass is set in the case above the dial u' .

Suitable dating devices are provided, herein represented as dating-wheels 2 3 4, arranged to be turned by a thumb-screw 5 in any usual or suitable manner.

It will be seen that the printing devices of the time-stamp herein represented are adapted to be moved forward step by step by the electro-magnet d^4 , energized in any usual or suitable manner, and that the disk e^2 is turned once in twelve hours to present A or P, as desired, and that the dating devices are set up by hand in any usual or suitable manner.

I claim—

1. In a time-stamp, an hour-shaft having on it at one end a hand or pointer, a minute-shaft revolving about the hour-shaft and having at one end a hand or pointer, a dial-plate concentric with said shafts and with which dial the hands or pointers co-operate, a hand on the opposite end of the hour-shaft, a visible auxiliary dial with which it co-operates, and an actuating-train for said hour and minute shafts, combined with a platen and an electro-magnet to move said platen against the dial-plate in the direction of its axis, substantially as described.

2. In a time-stamp, an hour-shaft having on it at one end a hand or pointer, a minute-shaft revolving about the hour-shaft and having at one end a hand or pointer, a dial-plate concentric with said shafts and with which dial the hands or pointers co-operate, a hand on the opposite end of the hour-shaft, a visible auxiliary dial with which it co-operates, and an actuating-train for said hour and minute shafts, combined with a platen movable against the dial-plate in the direction of its axis, and means to move said platen, substantially as described.

3. In a time-stamp, an hour-shaft having on it at one end a hand or pointer, a minute-shaft revolving about the hour-shaft and having at one end a hand or pointer, a dial-plate concentric with said shafts and with which dial the hands or pointers co-operate, a hand

on the opposite end of the hour-shaft, a visible auxiliary dial with which it co-operates, an actuating-train for said hour and minute shafts, the fixed stud *e*, having thereon 5 the character M, the movable stud adjacent thereto having on it the characters A P, and means for moving it automatically, combined with a platen, and an electro-magnet to move said platen against the dial-plate in the di-

rection of its axis and also against said fixed 10 and movable studs, substantially as described.

In testimony whereof I have signed my name to this specification in the presence of two subscribing witnesses.

HENRY A. CHASE.
